CLAIM

The ornamental design for a combined tape and note dispenser, as shown and described.

DESCRIPTION

FIG. 1 is a perspective view of the combined tape and note dispenser.

FIG. 2 is a right side elevational view, the left side elevational view being a mirror image thereof.

FIG. 3 is a top plan view.

FIG. 4 is a front elevational view; and,

FIG. 5 is a rear elevational view thereof.

The broken line showings of the roll of tape and the pad of note paper are for illustrative purposes only and form no part of the invention.
